FLAT SCREEN

Clarence L. Durkee, Wausau, Wis.

Application August 4, 1934, Serial No. 738,420

4 Claims.

(Cl. 92—32)

This invention is concerned with the paper industry and resides in an improved flat screen wherein the immediate structural support of the vibrating diaphragm bottom members serves also 5 as the support and reaction-absorbing member of the vibration-producing mechanism. The machine of this invention is adapted to the use of high strength materials, and the use of protective linings for preserving the life of the 10 equipment and preventing contamination of the material which is to be treated.

Flat screens, as they are known in the art, are widely used in the paper industry. In these devices the essential member is a slotted plate 15 having very fine openings. This plate is supported between the bottom and the top of an open trough. Pulp which is to be treated is delivered into the trough suspended in water. The bottom of the trough beneath the plates is 20 of a flexible construction and is vibrated at a rate of approximately 500 to 1000 alternate displacements per minute. This produces an alternating flow of fluid through the slots in the plate which, nevertheless, due to the method of 25 feeding and drawing off product, on the average amounts to a downward flow. The oscillation of the fluid in the slots of the plate is essential to the bringing about of an orientation of the fibres such as will permit passage thereof 30 through the plate as well as the continued clearing of the plate openings of that objectionable portion of the pulp of excessive coarseness, which is to be ultimately disposed of by an overflow which is continually maintained above the 35 plate. The main portion of the fluid and pulp, however, which passes downwardly through the plates is carried away continuously from openings between the plates and the vibrating bottom.

40 Many variations in form have been employed in the construction of flat screens and from time to time substantial improvement therein has been made. However, prior to the time of this invention there has been one structural 45 feature in common with all the variations, namely; that the immediate structural support of the vibrating diaphragm bottom has been formed as a part of a rather long, troughlike vat, which is supported by legs or similar supports at extended intervals, while the mechanism which produces the vibrating movement has been supported on another independent structure placed entirely below the vat or on the floor.

50 Although the displacement of the diaphragm

in general practice amounts to only a fraction of an inch, the rate of alternate displacement is rather high and the weight of fluid above the bottom is substantial. Due to this high rate and the rather high inertia of the fluid undergoing acceleration, momentary stresses of high intensity and high frequency are continually produced in the machine. The reaction of the stresses in machines heretofore employed must be carried back to the cam support, eccentric, or 10 rockshaft, which constitutes the vibrating mechanism per se through the long, bridgelike support of the trough, down a column, and thence across the girt as the support of the vibration-producing mechanism is called.

15 These stresses operating on long moment arms produce large moments at the points of support, which accounts satisfactorily for the rapidity with which the structures are known to deteriorate. Flat screen vats have heretofore been 20 constructed largely of wood and the flexibility inherent therein probably accounts to a large degree for whatever practicability they may possess. With the high alternate stresses, however, and the flexibility of the structure, vibration difficulties are not only rife throughout the 25 machine, but extend to the problem of supporting the machine itself and the buildings wherein the machine is housed.

30 In the machine of this invention, however, the reactive supports of the vibration-producing mechanism itself are associated with and made practically integral with the immediate structural support of the flexible bottom and in this way reactions produced by the accelerations of 35 the fluid are absorbed in the immediate neighborhood where created and are not permitted to travel through a long, bridgelike portion of the structure, thence downwardly through columns, and back through the floor or the girt to 40 the vibration-producing mechanism. In this way reactions are kept sufficiently closely associated so that elastic deformation of parts is reduced to a minimum and a measure of dynamic balancing of the structure is obtained.

45 Due to the elimination of prohibitive stresses and the suppression of vibration, highly rigid materials, such as steel, may be employed, creating a structure of high strength and rigidity, and thus permitting the embodiment of the machine in a relatively permanent type of structure in contrast to rapidly deteriorating wooden 50 structures heretofore considered essential. In this way all the disadvantages of wood, including its propensities to become water-soaked, and 55

thus to prevent application of protective coatings and consequently to rot and become extremely unsightly, as well as its clumsy and space-consuming nature, are avoided. Further in the machine of this invention fitting of plates is easy on account of the permanent alignment of the main structure and no swelling, shrinking, or warping, as in wood structures, disturbs this alignment.

If the pulp to be treated in the machine of this invention is in any way corrosive or subject to contamination by contact with steel, practically indestructible lining materials, such as rubber, lead, Monel metal, and the like, may easily be incorporated, altered, or replaced without the necessity for any new construction or new fittings of any sort. If the rubber diaphragm beneath a particular frame becomes damaged, its replacement may be accomplished simply and without disturbing the remaining machine. The edges of the diaphragm are not exposed to fluid and, therefore, fabric is not destroyed or attacked.

The machine of this invention is best described by reference to the accompanying drawings, wherein

Fig. 1 shows a side view of the machine, portions being broken away;

Fig. 2 is a section taken at the line 2—2 of Fig. 1;

Fig. 3 is a section taken at the line 3—3 of Fig. 1, showing details;

Fig. 4 is a section taken at the line 4—4 of Fig. 3, showing details, including a modified form of sealing strip;

Fig. 5 is a section taken at the line 5—5 of Fig. 2, showing details;

Fig. 6 is an enlarged detail view, with portions broken away, of the eccentric.

As shown in Fig. 1, the machine of this invention is characterized by its self-contained appearance arising out of the fact that the vat proper as well as the rock-shaft, or any other vibrating mechanism or medium and diaphragm connections, derive their support from the same principal supporting members. These members are shown in Fig. 1 as the side-supporting channels 1 and 2. The channel 1 has been broken away with other parts of the machine to reveal a sectional view on the left of Fig. 1, but both channels run from a supporting pier 3 to a supporting pier 4 and form the principal supporting members of the entire machine and give it the desired elevation. The channels 1 and 2 are aided in their function as supporting members by the vat sides 5 and 6, shown best in Fig. 2. The vat sides 5 and 6 are formed of strong, structural, channel shapes which extend throughout the length of the entire machine. The vat side 6 is spaced apart from the support member 2 by outlet boxes 8, which will be described more in detail. Said outlet boxes 8 are arranged at intervals and between the same are through-bolts 7 which pass through the webs of channel 2 and vat side 6, binding these members securely against the upper and lower sides of the outlet boxes 8, thus uniting the entire side of the machine into one practically rigid member. The other vat side 5 is spaced from the support member 1. Between the two and uniting the same into one practically rigid member are sectional diaphragm clamp angles 9 which are bolted to the vat side 5 by bolts 10, holding therebetween flexible diaphragms 12, to be described more in detail, and also bolted to supporting member 1 by bolts 11. The clamp

angles 9 are in short sections, as shown, and are easily removable by removing bolts 10 and 11. The two sides of the machine are thus shown to consist of two rigid arrangements of high strength.

At intervals, as shown in Fig. 1, the supporting members 1 and 2 are joined by cross-tie members 13, which are in the form of T section structural shapes. The cross-ties 13 are rigidly riveted to the supporting members 1 and 2 by rivets and angle brackets 14. At the extremities of supporting members 1 and 2 there is securely riveted in place an end channel 15, as shown in Fig. 1. The box structure formed by the supporting members 1 and 2 and the cross-ties 13 not only adds further to the rigidity of the entire machine, but also provides for the support of a rock-shaft or vibration-producing mechanism. Securely bolted to the cross-ties 13 and the end member 15 are pillow block bearings 16, 17, 18, 19 and 20. These are coaxially aligned for the rotational support of a rock-shaft 22. Shaft 22 is formed from a square steel bar, as better shown in Fig. 2, having cylindrical sections formed therein, as shown by the dotted circle in Fig. 2. The cylindrical sections are located to coincide with bearings 16, 17, 18, 19, and 20. The rock-shaft 22 thus derives its entire support directly from the main supporting structure of the entire machine.

The vibrating movement in this particular case, although other methods may likewise be employed, such as cams, etc., is communicated from the rock-shaft 22 to the diaphragm assembly through rocker arms 23—23 and 24. 30 Rocker arm 24 is clearly shown in Fig. 2 and is shown as consisting of two sections divided along a diagonal of shaft 22. The two sections are adapted to be drawn tightly against the shaft 22 by bolts 25, making it possible to maintain this connection absolutely secure regardless of wear. One of the sections of rocker 24 is furnished with a jaw-clamp and clamping screw 27 for securely gripping the rocker pin 26. The other section of the rocker arm 24 is furnished with the socket portion 28 of a ball and socket joint. Seated within the socket 28 is a ball 29 which is carried upon upper female part 30 of a right- and left-hand screw coupling 31. The lower female portion of the coupling is formed integrally with the casing 32 of a variable eccentric.

The variable eccentric is shown in detail in Fig. 6. It comprises the casing 32 in which a bearing 33 is held in place by the keeper plate 34. The bearing 33 surrounds an eccentric sleeve 35 having a bore eccentrically placed with respect to its cylindrical outer surface upon which the bearing 33 rests. The eccentric bore fits snugly upon a main eccentric shaft 36 so that the eccentric sleeve may turn thereon to vary the effective eccentricity of the outer cylindrical surface of the sleeve 35. The sleeve 35 is provided with a shoulder which faces a flange 37 formed integrally with the main eccentric shaft 36. Studs 38 pass through the flange 37 into the shoulder of the eccentric sleeve 35 so that said sleeve may be held in any of several various positions desired with respect to the main eccentric shaft 36. The main eccentric shaft 36 is journaled to turn in bearings 39, the latter being secured to the floor, as shown in full lines in Figs. 1, 2, and 6, or, if preferred, to the main frame of the machine, as shown in dotted lines in Fig. 2, or in any other conven-

tional location. If the building in which the machine is to be housed requires that vibration be reduced to a minimum, the location of the eccentric shown in dotted lines or its equivalent is to be preferred. However, in many cases this may be neither necessary nor desirable.

The rocker arms 23 above referred to and shown clearly in the drawings are similar in all respects to the rocker 24 except that no socket portion is employed. The rockers 23-23 and 24 are arranged in alternation so that rocker pins 26 fall alternately upon the right and left sides of shaft 22.

Diaphragm shoes 40 are pivotally mounted on 15 rocker pins 26 and extend upwardly therefrom to form flat, horizontal, rectangular surfaces between the vat sides. The diaphragm shoes are arranged in right and left-hand order corresponding to the placement of the rocker arms 20 23-23 and 24, as appears in Figs. 1 and 2. Above the diaphragm shoes and clamped securely thereto are flexible rubber fabric dia- 25 phragms 12, heretofore referred to. The dia- phragm material is of a construction strong enough so that the diaphragm shoes combine therewith in such manner that these two mem- bers furnish one another mutual support and no guiding of the diaphragm shoes 40 is necessary other than that furnished by the dia- 30 phragm 12.

The diaphragms 12 are clamped to the lower portion of the vat so as to completely seal the same except for the outlet boxes 8. As shown in Figs. 1 and 4, the vat is divided into frames 35 by bearers 41 which are placed crosswise at intervals between the diaphragm shoes 40. As shown clearly in Fig. 4, the bearers 41 are furnished with a spreading base through which bolts pass downwardly through the diaphragm 12 and clamping angles 42, where they are tightly held in place by means of nuts, thus forming a rigid, water-tight connection between the dia- 40 phragm 12 and the bearers 41. As shown in Figs. 2 and 3, the diaphragm 12 extends out- 45 wardly between the vat side 5 and the clamp angles 9, thus providing a combined, water-tight connection and support. The outlet boxes 8 extend into the vat, one into each frame, and carry a flange abutting at each end against 50 the sides of the bases of bearers 41 and having its lower surface flush with the lower surface of the bearer bases. The remaining side of the diaphragm 12 is brought to a rigid, water-tight connection with the flange of the suction boxes 55 8 by bolts 43 and clamping bars 44.

The screen proper, composed of plates 45, is clamped into the vat in water-tight connection therewith. For this purpose, transversely dividing each frame, are the struts 46, having a 60 dove-tailed boss transversely formed in the upper side thereof. The beveled edges of the plates 45 are placed under the dove-tail, as shown most clearly in Fig. 4. The plates 45 ex- 65 tend over and rest upon the upper surface of bearers 41, a gap occurring between adjacent margins of consecutive plates. Into these gaps wedge bars 47 are inserted and are forced down- 70 wardly into place by hold-down screws 57, which are mounted in replaceable, inclined blocks 58, as shown most clearly in Fig. 3. The plates 45 are thus wedged and held longitudinally in water-tight connection with their supporting members. To insure water-tightness along the 75 margins of the plates facing the vat sides, sealing strips 50 are employed. The sealing strips 50

are likewise securely held in place by hold-down screws 55 acting in inclined blocks 56. In the case of the inclined blocks 58 and 56, an inclined projection is provided on each, which acts against an apertured plate let into the trough sides 53. The action of the blocks 56, therefore, is to simultaneously jam the sealing strips 50 against the edges of the plates 45 and against the trough side members 53. A sealing felt 51 insures a leak-proof connection. The inclined 10 blocks 56 and 58 are easily detachable and may be quickly replaced in case of breakage or stripping of the threads. The sealing strips 50, as shown in Fig. 1, completely conceal the blocks 58 and the screws 55, as shown best in Fig. 2, 15 are the only projections. This contraction tends to eliminate accumulations of pulp which decompose and contaminate the product, because there are very few projections where pulp may accumulate. 20

In Fig. 4 another form of sealing strip is shown. In this case yokes 49, which are replaceable, serve as a mounting for the hold-down screws 48. The screws 48 force the locking bars 47 in place and also carry a jam nut which 25 acts against the sealing strips 59, holding the same securely in place against the jam cords 60.

The bearers 41, struts 46, outlet boxes 8, screen plates 45, and the like, are suitably formed from materials well adapted to resist corrosion and 30 for this reason the only structure not conveniently or economically formed of non-corrosive material are the two vat side members 5 and 6. However, they may be of steel and suitably lined. As shown in Fig. 3, a protective coating in the form of a lead or cadmium, ad- 35hering, or other suitable coating may be pro- vided with the greatest ease and convenience, or, if desired, the element 55 may be non-adhering sheet material of whatever composition the 40 particular material being processed demands.

As shown in the drawings, the rock-shaft 22 is supported securely by the same structural members which provide the support for the dia- phragm. The reaction, therefore, resulting from 45 the acceleration of the fluid is communicated directly to the rigid sides of the machine and thence back to the shaft 22 without having to travel more than the space of one frame. In the case of a flat screen, which may be adjusted 50 for very strong agitation, the return of the reac- tion to the shaft 22 may be even further short- ened by bolting the clamp angles 42 securely 55 to the cross-tie members 13. In case of a desire to produce a machine as completely rigid and immovable as possible, cross-ties 13 may be placed together with bearings 17 at each division 60 between frames and securely bolted to the clamp angles 42. However, this expedient is not always essential, as is shown in Fig. 1, partly because 65 of the fact that alternate diaphragms are pur- suing opposite movements and in this manner offset and balance one another to a certain extent. As shown in Fig. 2, the eccentric may be formed as a part of the frame of the ma- chine and by so doing no reaction between the 70 floor and the machine proper occurs. As pointed out above, this method of supporting the eccentric may be resorted to when it is desired to protect the building in which the machine is housed from vibration as far as possible.

From the above and from the self-contained nature of the machine, as appears in the drawings and in the description, the advantages of 75

the machine of this invention over those heretofore employed are numerous. One advantage resides in the fact that it is often convenient to pitch the screen in one direction or another, in which case with the machine of this invention the ball and socket joint 28-29 accommodates for the angularity introduced by the pitch. In machines heretofore used a separate adjustment of the length of each connecting-rod as well as for angularity was necessary in case the inclination of the screen was different from that of the floor. In cases where the eccentric is mounted on the frame of the machine itself these difficulties are also entirely obviated.

Although other appropriate means for oscillating the diaphragms may be employed with equal success in the machine of this invention, only one specific means for accomplishing this purpose is shown, namely: a rock-shaft. The rock-shaft, however, of itself is possessed of certain advantages arising out of the employment of a squared section and the manner of clamping the rocker arm members thereto. In this way set-screws and keyways, that are susceptible to wear and looseness, as have heretofore been employed, are eliminated.

The eccentric employed may be varied as to its stroke, as shown in Fig. 6, and explained above 30 and this is of a substantial advantage in obtaining the maximum effectiveness from the screen. For example, when a long, flat screen is employed, having about twenty-four or more frames, it is often advantageous to oscillate the 35 diaphragms in different sections in different manners so that the more decidedly improper portions of the pulp may be quickly eliminated by rapid agitation in that part of the screen which treats the pulp first and a more gentle, discerning treatment can be provided at the final end of the screen.

When screens are arranged in long structures the joining of the ends of the members is an 40 important matter. The machine of this invention being adapted for construction of steel, it is particularly well adapted for the joining of the members end to end by welding or splicing without loss of space. In the flat screens heretofore employed the splicing of the woolen ends 45 has been a problem which has not been satisfactorily solved. The splices not only are difficult to make, but do not remain tight for more than a rather short period. In the screen of this invention the joining of the sections may be 50 accomplished easily and when completed these joints will remain secure through the entire 55 life of the machine.

If two lines of screens are arranged parallel to each other in close proximity, a single eccentric placed between the machines can be employed to actuate the rock-shaft mechanism of both machines. In this way two machines may be counterbalanced one against the other, providing a further means for the elimination of 60 vibration.

The usual form of construction now employed involves the use of two screen plates above each diaphragm. It should be understood, however, that this invention may be embodied in a machine in which this custom is entirely disregarded, for example, the partitions 41 shown in Fig. 1 may be eliminated and a single diaphragm through the entire screen employed. By so 65 doing a substantial reduction in the materials and parts required may be effected and the cost

of the machine substantially lessened. In such cases two diaphragms, limited in extent only by the strength of the materials employed, may be balanced one against the other and the machine operated fully in accordance with the disclosure 5 of this invention.

A further advantage of this invention lies in the fact that it is a simple matter to reduce the distance between diaphragm and screen plates to a minimum and it has been found when this 10 distance has been reduced to three inches or less a great reduction in inertia of the fluid to be moved permits of substantial saving. In such a case the load on bearings and other moving parts, as well as upon the supporting structure, is diminished to such an extent that a far lighter, simpler, and more economical construction may be employed with no loss of capacity or any diminution of the high velocities which are necessary to purge and prevent lodgment of 20 pulp and lumps in the screen plates or the cells of the vat.

In the machine of this invention the diaphragm edges are carried to the outside of the machine and there is no liquid in contact therewith. This is of importance in that the fabric core of the diaphragm material has a tendency to act as a wick and to carry moisture into the interior of the material, causing rapid deterioration thereof. The diaphragm is held also chiefly 30 by members which are not exposed to the liquid, and these may be made of ordinary materials in so far as corrosive effect is concerned and, consequently, can be more cheaply made.

While the above description and the accompanying drawings have been employed to describe in detail the machine of this invention in connection with one specific embodiment thereof, it is intended that protection of Letters Patent to be granted hereon be not necessarily 40 limited thereby, but extend to the full scope of the invention as represented by the claims appended hereto.

What I claim is:

1. In a machine of the character described, the 45 combination comprising longitudinal supporting members, cross members therebetween, screen plates mounted thereon, diaphragms secured thereunder, bearing cross supports positioned under said cross members and secured to 50 said longitudinal members, and an oscillatable rockshaft communicating with said diaphragms so as to actuate the same carried by said bearing cross supports.

2. In a machine of the character described, 55 the combination comprising longitudinal supporting members, cross members therebetween, screen plates mounted thereon, diaphragms secured thereunder, bearing cross supports positioned under said cross members, an oscillatable 60 rockshaft having squared portions carried by said bearing cross supports, rocker arms clamped to said squared portions of said shaft, and diaphragm shoes actuated by said rocker arms to communicate an oscillating movement 65 to said diaphragm.

3. In a machine of the character described, the combination comprising longitudinal supporting members, cross members therebetween, screen plates mounted thereon, diaphragms secured thereunder, bearing cross supports positioned under said cross members and secured to 70 said longitudinal members, an oscillatable rockshaft carried by said cross supports, rocker arms secured to said shaft, diaphragm shoes actuated 75

5 by said rocker arms to communicate an oscillating movement to said diaphragms, and an eccentric mounted upon said longitudinal supporting members and connected with said oscillating shaft for the actuation thereof.

4. In a machine of the character described, the combination comprising a vat, screen plates therein, diaphragms disposed therebelow, vibration-providing means for actuating said diaphragms, vat sides surrounding and extending above said screen plates, apertured bearing plates secured to said vat sides, wedge bars

holding said screen plates in position, jackscrews bearing against said wedge bars and having a hook portion engaging some of said bearing plates, sealing strips at the juncture of said vat sides and said screen plates, and jackscrews 5 bearing upon said sealing strips and having an inclined hook portion engaging some of said bearing plates so that said jackscrews exert a combined downward and outward pressure against said sealing strips. 10

CLARENCE L. DURKEE.
